UNITED STATES PATENT OFFICE.

ARTHUR W. HAMBY, OF COLUMBIA, SOUTH CAROLINA.

ANTIGLARE ATTACHMENT FOR AUTOMOBILE HEADLIGHTS.

Application filed November 21, 1925. Serial No. 70,685.

This invention relates to glare controlling attachments especially adapted for use on the headlights of automobiles, locomotives and the like.

5 Briefly stated, an important object of this invention is to provide a glare controlling means for headlights which may be attached to a conventional headlight without any alteration whatever and which may therefore 10 be applied without the exercise of unusual skill.

Another important object of the invention is to provide a headlight attachment of the character specified which is of highly 15 simplified construction, convenient to operate, and cheap to manufacture.

Other objects and advantages will be apparent during the course of the following description.

20 In the accompanying drawing forming a part of this application and in which like numerals are employed to designate like parts throughout the same,

Figure 1 is a perspective of the attachment in use;

Figure 2 is a horizontal sectional view illustrating a headlight equipped with the improved glare controlling attachment;

Figure 3 is a group perspective of the 30 attachment;

Figure 4 is a front elevation of a slight modification of the invention.

Figure 5 is a side elevation of the form of invention shown in Figure 4, the shutters in Figure 5 being open;

Figure 6 is a front elevation illustrating another form of the invention;

Figure 7 is a side elevation of the form of invention shown in Figure 6;

40 Figure 8 is a front elevation illustrating a slight further modification of the invention;

Figure 9 is a side elevation of the form of invention shown in Figure 8.

45 In the drawing the numeral 5 designates a conventional headlight within the shell of which a reflector 6 of parabolic or other form is located.

Figure 2 illustrates the usual socket member 7 which as is well known is adapted to receive the base 8 of an incandescent bulb 9, the base being provided with lugs 10 which engage in slots in the socket member whereby to hold the bulb firmly in place.

55 As previously stated, the invention form-

ing the subject matter of this application is essentially in the nature of an attachment for a conventional headlight and it consists of a frame having diverging arms 12 arranged at opposite sides of the bulb 9 and connected at the rear ends thereof to an attaching ring 14, the ring 14 being adapted to be connected in the manner shown in Figure 2. It is thus seen that the attachment may be employed without changing the style of the bulb 9 or without the employment of separate fastening devices and what is more important without altering the design or shape of the electric bulb or headlight.

The forward portions of the diverging arms 12 have connection with an annulus 16 to which a shutter 18 is horizontally hinged as indicated at 19. More specifically the lower portion of the annulus 16 is provided with a pair of apertured ears 20 between which a hinge barrel or ear 21 of the shutter is positioned and these parts receive a hinge pin 22. When the shutter is in its normal open position it may rest upon a forwardly extending approximately horizontal supporting bracket 26 extended forwardly from the lower portion of the annulus 16. The bracket 26 may be magnetized if desired so as to prevent uncontrolled movement of the shutter when open.

The shutter 18 may consist of a rim having a lens 27 of some transparent or translucent material. If desired the shutter may be of solid metal or it may be of glass having prisms designed to throw the light downward. In fact the shutter 18 may be of any material or form capable of deflecting the objectionable light rays when the shutter is in its elevated position in front of the light bulb.

Figures 1, 2 and 3 clearly illustrate that a magnet 30 is positioned at one side of the annulus 16 and is secured thereto by a strap 31. The strap may be welded or otherwise secured to the annulus 16. The magnet 30 has connection with electric wires which may extend from a remote point. Of course the electric wires have connection with a source of energy such as a battery and a switch may be located at any place within convenient reach of the operator. For example the switch may be located on the steering column, the steering wheel, or the dash of the motor vehicle if, indeed, the

invention is employed on a motor vehicle. However, it is to be remembered, that the invention is not in any way restricted in its application to an automobile as it is 5 equally adaptable to the headlight of a locomotive or the like. When the magnet 30 is energized the lug 36 on the shutter 18 will be attracted so that the shutter will promptly move to closed position directly 10 in front of the light bulb. This of course obscures the objectionable light rays which emanate from the central portion of the headlight. However, the movement of the shutter to a position directly in front of 15 the light bulb does not in any way interfere with the light rays reflected from the outer portion of the parabolical reflector and therefore an annular beam of light will go forward from the lamp. This annular beam 20 of light will be sufficient to illuminate the roadway a reasonable distance in advance of the automobile, but will not be objectionable to the drivers of approaching vehicles. In the form of invention illustrated in 25 Figures 4 and 5 the frame is provided with the tubular attaching portion 40 having the forwardly directed diverging arms 41 to which the annulus 42 is connected. Figure 5 clearly illustrates that a pair of semi-circular shutters 43 are horizontally pivoted 30 between their upper and lower edges thereof to the annulus 42 as indicated at 44 and the shutters have connection with a rod or link 46 through the medium of loops 47. The 35 rod 46 is positioned below and in the field of magnetic force of a magnet 49 and when the magnet is energized from a remote point the rod is lifted to hold the shutters in open position and thereby permit of the uninterrupted passage of the light rays. In this form of the invention the magnet 49 must continue to be energized to retain the rod 46 in elevated position. When it is desired to obscure the light emanating directly from 40 the bulb the supply of current to the magnet 49 may be cut off to allow the weight of the rod 46 to move the shutters 43 to closed and overlapping position as shown in Figure 4. It is believed to be obvious that 45 the shutters will remain in this position until the magnet is again energized. When the shutters are in their closed positions, as shown in Figure 4, the direct light rays are interrupted, but light beams 50 may go forwardly from the reflector, but will be insufficient to cause annoyance to the drivers of approaching vehicles. In the form of invention shown in Figures 5 and 7 the shutter support is in the form 55 of an annulus 50 having the arms 51 which converge toward an attaching member by means of which the device may be quickly secured to a conventional headlight without any modification whatever. 60 In this form of invention the semi-circular shutters 53 are vertically pivoted between their opposite edges thereof as indicated at 54 and are connected by means of a magnet responsive rod or link 56 arranged horizontally as shown in Figure 6. 70 The edges of the vertically pivoted shutters 53 are provided with the loops 58 to which the magnet responsive element 56 is connected. In carrying out this form of invention two 75 magnets 60 and 61 are arranged at opposite sides of the frame 50 and when separately energized will draw the rod 56 in the proper direction, that is to say, when the magnet 61 is energized the shutters will be moved to closed position as shown in Figure 6. On the other hand when the magnet 60 is energized the shutters 53 are moved to the open position as shown in Figure 7. It is believed to be obvious that the magnets 60 and 80 85 61 are not operated at the same time, but operated separately to either close or open the shutters. The magnets 60 and 61 have connection with a suitable source of electrical energy and a switch of any type may be employed in the circuit so that the operator may at will interrupt the light rays emanating directly from the light bulb in advance of which the shutters are located. In the form of invention illustrated in 90 Figures 8 and 9, the shutter supporting ring or annulus 70 is provided with the arms 71 to which an attaching collar or member is connected whereby the ring may be mounted slightly in advance of a light bulb 95 without in any way changing the construction of the associated headlight. This form of the invention is especially adapted for interrupting only a portion of the light rays which emanate directly from the light bulb and by reference to Figure 8 it will be seen that the single shutter 75 which is of semi-circular formation is vertically hinged to the annulus 70 as shown at 76. The semi-circular shutter 75 is provided adjacent the lower portion thereof with a lug or ear 78 in the field of magnetic influence of a magnet 80, the magnet being secured to the annulus 70 by a bracket 83. Of course the magnet 80 has electrical connection with a source 100 of current and as stated in connection with the other forms of invention a switch may be placed at a suitable point in the circuit. Of course the shutter may be two-thirds or any other part of a complete circle without 105 departing from the invention. 110 The form of invention shown in Figures 8 and 9 will interrupt only those rays which are objectionable to the drivers of approaching automobiles and will allow light rays to go forwardly directly from the light bulb and illuminate the side of the roadway opposite the drivers of approaching vehicles. It will therefore be seen that the attachment 115 shown in Figures 8 and 9 may be advanta- 120 125 130

geously employed for avoiding objectionable light rays and at the same time allowing the right hand side of the road directly in advance of the automobile to be fully 5 illuminated.

The invention which is essentially in the nature of an attachment may be applied to the lantern, the socket member or the bulb.

The invention forming the subject matter 10 of this application is as demonstrated by the large number of modifications illustrated capable of a variety of mechanical expressions and it is therefore to be understood that the forms of the invention herewith shown 15 and described are to be taken merely as preferred examples of the same and that such minor changes in arrangement and construction of parts may be made as will remain within the spirit of the invention and 20 the scope of what is claimed.

I claim as my invention:

1. As an article of manufacture, an attachment for headlights comprising a frame having an attaching band, forwardly extending arms and an annular support, a shutter connected to said support and having a magnet responsive element, and an electro-magnet carried by said annular support and adapted to operate said shutter.
2. As an article of manufacture, an attachment for headlights of conventional design comprising a frame having an annulus, and arms provided with means whereby the frame may be detachably positioned about 25 a light bulb, a shutter hinged to said annulus and adapted to be positioned in advance of the light bulb to obscure light from the same, and an electro-magnet carried by said annulus, said shutter being provided 30 with a magnet responsive element in the field of magnetic influence of the magnet whereby when the electro-magnet is energized the shutter will be moved to one of its extreme positions.
3. As an article of manufacture, an attachment for headlights of conventional design comprising a frame having an annular attaching portion, forwardly directed arms and an annulus, a shutter horizontally 35 hinged to the lower portion of said annulus and having a magnet responsive lug, and an electro-magnet carried by said annulus and adapted to exert a magnetic influence on 40 said lug to draw the shutter to closed position.

4. As an article of manufacture, an attachment for headlights of conventional design comprising a frame having an annular attaching portion, forwardly directed arms and an annulus, a shutter horizontally 45 hinged to the lower portion of said annulus and having a magnet responsive lug, an electro-magnet carried by said annulus and adapted to exert a magnetic influence on 50 said lug to draw the shutter to closed position, and an arm to support said shutter in open position.

5. As an article of manufacture, an attachment for headlights comprising a frame having an attaching band, forwardly extending arms and an annular support, a shutter connected to said support and having a magnet responsive element, an electro-magnet carried by said annular support and 55 adapted to operate said shutter, and means carried by said annulus for supporting said shutter in open position within the field of magnetic influence of said magnet.

6. As an article of manufacture, an attachment for headlights comprising a frame having an attaching band, forwardly extending arms and an annular support, a shutter connected to said support and having a magnet responsive element, an electro-magnet carried by said annular support and 60 adapted to operate said shutter, and magnetized means carried by said annulus for supporting said shutter in open position within the field of magnetic influence of said magnet.

7. As an article of manufacture, an attachment for headlights of conventional design comprising a frame having an annulus, and arms provided with means whereby the frame may be detachably positioned about 65 a light bulb, a shutter hinged to said annulus and adapted to be positioned in advance of the light bulb to obscure light from the same, an electro-magnet carried by said 70 annulus, said shutter being provided with a magnet responsive element in the field of magnetic influence of the magnet whereby when the electro-magnet is energized the shutter will be moved to one of its extreme 75 positions, and means carried by said annulus and designed to support said shutter in a position for actuation by said magnet.

In testimony whereof I affix my signature.

ARTHUR W. HAMBY.
